STACY B. HASELTINE, OF CHICAGO, ILLINOIS, ASSIGNOR TO WILLIAM H. MINER, OF CHICAGO, ILLINOIS.

DRAFT-YOKE FOR RAILWAY-CARS.

1,130,083.

Specification of Letters Patent. Patented Mar. 2, 1915.

Application filed November 24, 1913. Serial No. 802,670.

To all whom it may concern:

Be it known that I, STACY B. HASELTINE, a citizen of the United States, residing at Chicago, in the county of Cook and State of Illinois, have invented a certain new and useful Improvement in Draft-Yokes for Railway-Cars, of which the following is a full, clear, concise, and exact description, reference being had to the accompanying drawings, forming a part of this specification.

My invention relates to improvements in draft yokes for railway cars.

The object of my invention is to provide a draft yoke of simple construction and efficient operation, and one in which the draw bar may be readily removed therefrom, and in which the draft gear may be readily dismounted.

In the drawings forming a part of this specification—Figure 1 is a plan view partly in horizontal section on line 1—1 of Fig. 2 of a draft yoke embodying my invention; Fig. 2 is a central vertical longitudinal section on line 2—2 of Fig. 1 showing the parts of the yoke in assembled position; Fig. 3 is a vertical longitudinal section showing the parts thereof detached from coupler. Fig. 4 is a cross section taken on line 4—4 of Fig. 2; Fig. 5 is a rear end elevation taken at line 5—5 of Fig. 2; Figs. 6 and 7 represent a modification, Fig. 6 being a vertical longitudinal section of the rear end of a modified form of the draft yoke taken on the line 6—6 of Fig. 7, and Fig. 7 a rear elevation thereof taken at line 7—7 of Fig. 6.

Referring to the drawings the numeral 8 represents a draw bar, the rear end thereof only being shown in the drawing; 9 the butt of said draw bar forwardly provided with the shoulders 10, 10, the said draw bar being of a standard well known type.

The numeral 11 represents a draft yoke comprising three main portions, to-wit: an upper arm 12, a lower arm 13, and a rear connecting member 14. The yoke 11 is forwardly provided with a hollow box-like member 15, which is preferably integral with the upper limb 12 of the yoke, and bears a transverse inwardly turned lug 16 at its forward end adapted to engage with the upper shoulder 10 of the draw bar. The said hollow box-like member is adapted to receive the draw bar, and also to receive the

forward end of the lower limb 13 of the yoke, the said lower limb being provided with a transverse inturned gib 17 adapted to engage with the lower shoulder 10 of the draw bar, and also provided with suitable means, preferably the lugs 18, 18, downwardly extended from the forward end thereof, and engaging the lower member 19 of the hollow box-like member 15 to hold the forward end of the said lower limb in engagement with the draw bar. The rear end of the upper limb of the yoke is adapted to engage with, preferably by pivotal means, the connecting member 14. The connecting member 14 comprises a pair of arms 20, 20 engaging either side of the rear end of the upper limb of the yoke, and pivoted thereto by means of the pin 21 passing through said arms and through the slot 22 in said upper limb.

In preferable construction the rear end of the upper limb 12 is narrowed, as shown in Fig. 1 of the drawings, and the said narrow portion of thicker vertical dimensions, as shown at the numeral 23 of Fig. 2 of the drawings, so as to permit the engagement of the arms 20, 20 therewith without widening the yoke in its entirety, and without widening the upper limb thereof.

The connecting member 14 is provided between the arms 20 with a web 24 connecting the said arms 20, and preferably integral therewith, the same forming in preferable construction at its upper end a shoulder 25 to engage against the shoulder 26 formed by the depending portion 27 of the rear end of the upper limb 12 of the yoke. The said perforation 22 is sufficiently extended longitudinally to permit the connecting member 14 to be swung rearwardly upon the pivot 21 when the said pivot is moved to the forward end of the perforation 22 in the limb 12. At its lower end the connecting member 14 is provided with a key way formed preferably by the transverse slots 30, 30 in the arms 20, 20. A longitudinal recess 31 is provided in the lower end of the connecting member 14 to receive the rear end of the lower member 13 of the yoke, the said lower limb being provided with a transverse slot 32 to receive the key 33, which extends through said slot and through the perforations 30 in the connecting member 14. The lower member 19 of the hollow box-like member 15 is provided with a perfo-

110

ration 35 of sufficient dimensions to receive therethrough one of the lugs 18 with which the lower limb 13 is provided.

In disconnecting the draw bar from the 5 yoke, the key 33 is first removed after which the two arms or members of the yoke 12 and 13 are moved longitudinally relatively to each other, either by moving the member 12 forwardly or by moving the member 13 10 rearwardly until the front lug 18 drops into the perforation 35. This permits the arms of the yoke to separate a sufficient distance to give clearance for the abutments or shoulders 10 on the draw bar, whereupon the latter 15 may be taken out. In taking out the draft gear without taking out the draw bar, the key 33 will be removed as above described, after which the lower member of the yoke 13 will be pushed forwardly until 20 the lugs 18, 18 have passed out beyond the plate 19, whereupon the member 13 will drop down and may be pulled still farther and tilted downwardly sufficiently to provide clearance for removing the gear.

25 As shown most clearly in Fig. 1, the rear inner walls 50 of the gibs or lugs 16 and 17 on the yoke members, are curved to permit the draw bar to swing radially relatively to the yoke, it being understood that the inner 30 end of the draw bar is less in width than the distance between the vertical walls of the box-like member 15 as shown most clearly in Fig. 4.

In the modification illustrated in Figs. 6 35 and 7 of the drawings the upper limb 36 of the yoke is pivotally connected with a connecting member 38, the said connecting member 38 being provided at its lower end with a longitudinal recess 39 to receive the 40 rear end of the lower limb 40 of the yoke, the said lower limb being provided with a transverse slot 41, and the connecting member having transverse slots 42, 42 registering therewith for the passage of the key 43, 45 which secures the lower limb 40 to the connecting member 38. Preferably a cotter 44 is employed to secure the key 43 against accidental displacement. At its rear end the upper limb 36 of the yoke is laterally provided 50 with bearing faces 45, 45 to receive the inturned lugs 46, 46 with which the upper end of the connecting member 38 is provided, thus pivotally engaging the said connecting member 38 to the upper limb 36, the said 55 connecting member being also provided with a shoulder 47 engaging against the shoulder 48 formed by the depending portion 49 at the rear end of the upper limb 36 of the yoke to hold the connecting member and the upper limb in firm coengagement. The modification illustrated relates only to the rear end 60 of the yoke, the other parts of the yoke being

identical with the preferable form illustrated in Figs. 1 to 5 of the drawings.

I claim:—

1. In a draft yoke having upper and lower limbs adapted to engage a draw bar and a rear connecting member for said limbs, said connecting member being pivotally connected to one of said limbs, and adapted to be 70 keyed to the other of said limbs.

2. In a draft yoke for railway cars, upper and lower limbs adapted to engage a draw bar, a rear connecting member for said limbs and a key, the rear connecting member being 75 keyed to one of said limbs and secured to the other of said limbs, said connecting member being slidingly pivoted to said last mentioned limb when disengaged from the key.

3. In a draft yoke for railway cars, the 80 combination with a limb having a hollow box-like member to receive the draw bar and a detachable limb engaging the draw bar, of a connecting member for said limbs and a key, the connecting member being swingingly mounted on one of said limbs and 85 keyed to the other limb.

4. In a draft yoke for railway cars, a pair of limbs adapted to engage a draw bar at their one end and a member to connect said limbs at their other end, and a key, the said connecting member being swingingly mounted on one of said limbs, and having a recess 90 to receive the other of said limbs, the key being adapted to secure said limb within the 95 recess.

5. In a draft yoke for railway cars, a pair of limbs, a third member connecting said limbs at the rear ends thereof, and a removable transversely extending key engaging 100 said member and one only of said limbs for detachably holding the same together.

6. In a draft rigging for railway cars, a draft yoke comprising a pair of limbs and a separable connecting member therefor, one 105 of said limbs being provided with an integral band-shaped member adapted to receive a draw-bar.

7. In a draft rigging for railway cars, a draft yoke comprising a pair of limbs and a separable connecting member for said limbs, one of the limbs being provided with a band-shaped head adapted to receive a draw-bar, and one end of the other limb, both of said limbs engaging the draw-bar, the last mentioned limb being provided with a lug, and the band-shaped member being provided with an aperture to receive said lug on disengagement of the limbs of the yoke from the draw-bar.

STACY B. HASELTINE.
